George D. Moulton, Inventor
John Mc Spellman
Attorney.

UNITED STATES PATENT OFFICE.

GEORGE D. MOULTON, OF DENISON, TEXAS.

MAGNETIC SAFETY RAZOR.

Application filed January 25, 1923. Serial No. 614,880.

To all whom it may concern:

Be it known that I, GEORGE D. MOULTON, citizen of the United States, residing at Denison, in the county of Grayson and State of Texas, have invented certain new and useful Improvements in Magnetic Safety Razors, of which the following is a specification.

This invention relates to safety razors and 10 more specifically to the incorporation in such a razor of a permanent magnetic means.

The object of the invention is to provide a magnetic arrangement in the razor for the purpose of enabling the razor blades to 15 be picked up and placed in position upon the razor without the initial use of the fingers.

Another object of the invention is that it 20 obviates the need of a plurality of apertures usually present in a razor blade or element underneath the blade, such as in a duplex edge safety razor for immovably securing the blade in position.

The invention also has for an object, a 25 razor of the nature set forth capable of being manufactured at a nominal cost; and durable and having a neat and attractive appearance.

Proceeding in accordance with the drawings annexed hereto:

Figure 1 is a front elevational view of a safety razor embodying the invention.

Figure 2 is a longitudinal section of Figure 1.

Figure 3 represents a longitudinal section on Figure 4, the latter figure being a side view.

Figure 5 is a bottom view of the blade retainer with stem attached; and Figure 6 40 shows the blade with apertures.

Figure 7 is a plan view of the blade supporting element.

Figure 8 is a front elevational view of a modification of the razor.

Figure 9 is a longitudinal section on Figure 8.

Figure 10 is a longitudinal section of another modification of the razor; and,

Figure 11 is a side view in longitudinal section of Figure 8.

In the drawings more in detail, 1 denotes the razor blade retaining means which has

a stem 1^a. The stem is adapted to be inserted in the hollow handle 5, the latter having a screw cap 6. A blade supporting member 3 has an aperture C, see Figure 7, for the purpose of conformably receiving the enlarged portion 1^b of the stem and blade retaining member 1. The razor blade 2 and its supporting member 3 have like apertures b and c through which the enlarged portion 1^b is passed when the blade is in operable position.

The magnetic means comprises a magnet 3^a secured to the blade supporting member 3 and has a collar 4 through which the stem 1^a is inserted the collar being passed into the handle 5 to hold the magnet in position.

By the above arrangement, it will be seen that when the cap 6 is unscrewed the stem 1^a and retainer 1 may be lifted out and the blade removed. The magnet is thus exposed and can be placed against a new blade to pick up and move it into position without initially using the fingers to take up the blade.

In Figures 8, 9 and 11 are illustrated a modification of the magnet and the arrangement for securing it to the handle and other parts of the razor. In this arrangement the magnet is longer and differently shaped and the stem 1^a is shorter and is adapted to be seated in a solid handle 5. The handle is also screwed onto the collar 4 and the latter is screwed onto the stem.

Figure 10 shows a further modification and wherein the stem is shorter and the cap 6 has a tubular extension 6^a which is screwed onto the stem 1^a. The collar 4 is likewise longer and to it the handle is screwed.

It should be understood that further changes may be made in the arrangement and construction of the razor without departing from the spirit and meaning of the following claim.

What is claimed is:

In a safety razor, a substantially U-shaped magnet having an aperture in its base, a blade support carried by the free ends of the legs of the magnet, a blade on the support, the support and blade each having an aperture aligned with the space between the legs of the magnet, a handle engaged at one end with the base of the magnet, a blade

holder having a stem extending through the blade and support apertures and disposed in the space between the magnet legs, an aper-
5 tured connecting member arranged in the said aperture of the base of the magnet and receiving the lower end of the stem in its aperture, said handle having threaded con-

nexion with the connecting member, and means to move the stem and thereby to hold or to clamp the blade upon rotation of the handle.

In testimony whereof I have signed my name to this specification.

GEORGE D. MOULTON.
